UNITED STATES PATENT OFFICE.

HENRY C. MIELKE, OF ROCHESTER, NEW YORK.

OPHTHALMIC-LENS BLANK.

1,285,306.

Specification of Letters Patent. Patented Nov. 19, 1918.

Application filed December 26, 1917. Serial No. 208,775.

To all whom it may concern:

Be it known that I, HENRY CHARLES MIELKE, a citizen of the United States, and resident of Rochester, in the county of Monroe and State of New York, have invented 5 certain new and useful Improvements in Ophthalmic-Lens Blanks, of which the following is a specification.

The present invention relates to a blank 10 for forming a plurality of ophthalmic lenses, an object of this invention being to provide for reducing the cost of producing a lens of the type mentioned.

To this and other ends the invention consists of certain parts and combinations of parts, all of which will be hereinafter described, the novel features being pointed out in the appended claims.

In the drawings:

20 Fig. 1 is a sectional view through a cylinder showing the first steps of the present method;

Fig. 2 is an end view of the cylinder shown in Fig. 1;

25 Fig. 3 shows, in section, the cylinder divided into three segments or rings;

Fig. 4 is a side view of a forming wheel on which the cylinder segments or rings are molded;

30 Fig. 5 is an axial section through such forming wheel;

Fig. 6 shows, in section, the manner of forming the blank on the forming wheel from the ring segments shown in Fig. 3;

35 Fig. 7 is a perspective view of the completed ring blank before grinding and polishing;

40 Fig. 8 is a perspective view of the blank ground and polished showing the manner in which the individual lenses may be formed from the blank;

Fig. 9 is a face view of one of the individual lens blanks; and

45 Fig. 10 is a sectional view through the individual lens blank shown in Fig. 9.

According to this invention molten glass is formed into a hollow cylinder, as shown in Figs. 1 and 2, preferably by blowing the glass into a mold. After molding, the cylinder is annealed. The thickness of the wall of the cylinder varies with the focal power of the lenses, being, say, for instance, three millimeters. The outside diameter of the hollow glass cylinder depends on the base 50 curve of the lenses, being, say, for instance,

116 millimeters. The cylinder may be of any suitable length, say, for instance, 141 millimeters, which permits the cutting of three blank rings each having a surface width of 47 millimeters.

60 Each ring after being cut from the cylinder is heated to a plastic state, and is then applied to the mold wheel or former shown in Figs. 4 and 5. This mold wheel or former comprises, in this instance, three segments 65 3, each of which is supported by an arm or spoke 4 extending from a hub segment 5. The segments 5 fit on a spindle 6, being held against a shoulder 7 on said spindle by a tapered nut 8 adjustable on a screw threaded portion 9 on the hub segments 5. This nut permits the withdrawal of the spindle from the hub sections 5, so that the mold wheel or former may be collapsed. When the plastic ring 2 is applied to the former 70 or mold wheel, the parts are in the position shown in Figs. 4 and 5. The wheel is then rotated in a vertical plane and a roller 10, having a curved face 11 and side flanges 12, is brought into engagement with the plastic 75 ring and causes said ring to conform to the shape of the mold wheel or former 3. The periphery of the mold or former 3 may be flat or have any desirable curve transversely of its plane of rotation, so that a toric or 80 spherical curve may be provided on the inner face of the ring. The form of the face 11 of the roller 10 may be varied to produce a flat surface or any desired toric or spherical curve on the outer face of the ring. Owing 85 to the fact that the sections 3 are slightly spaced from each other, openings are provided in which portions of the plastic ring may be forced during rolling, so as to prevent the slipping of the plastic ring on the 90 mold wheel or former. The ring blank, after being shaped to correspond to the curved face of the mold wheel or former, and also to the curve of the roller, is removed from the mold wheel and annealed. The completed 100 blank before grinding and polishing is shown in Fig. 7 at 13, the internal transverse ribs on the ring indicating those portions which enter between the segments of the mold wheel. The ring may now be mounted 105 upon a suitable holder and ground and polished to the curvature desired.

Assuming when both sides have been completed that the convex side is a toric surface having a base curve of 6 dioptric power, 110

and the curve at right angles to this base curve of a dioptic power of 7.00; and the opposite surface a spherical curve of approximately -6.25 dioptic power, we have 5 what is known in the optical trade as "plano-cylinder toric +1.00 lens." The ring is then cleaned and inspected for flaws, focus and center.

From this ring, segments are cut to 10 provide different individual lens blanks. Assuming for a pair of eyeglasses that the right eye requires +1.00 cylinder axis 90, while the left eye requires +1.00 cylinder axis 180 size 38x42 mm, the two lenses are 15 cut from the ring blank in the manner shown in dotted lines in Fig. 8. Allowing 1 mm. for edging, it will be noted that from the ring blank a portion would be used or cut of the size 47x77 mm., whereas under 20 the old method a surface 47x94 mm. would be required—making a difference of 47x17 mm. saved or a saving of about 25% from the same amount of developed glass.

Furthermore, should a flaw be found in any portion of the ring, the defective portion 25 may be cut out without destroying so much glass as would be necessary should any individual lens be found defective under the old system.

What I claim as my invention and desire 30 to secure by Letters Patent is:—

1. A blank suitable for forming a plurality of ophthalmic lenses comprising a ring shaped member having a surface curved concentrically with the center of the ring 35 and also transversely of the plane of the ring.

2. A blank suitable for forming a plurality of ophthalmic lenses comprising a ring shaped member having two surfaces one 40 of which is convex and the other of which is concave, each surface being curved concentrically with the center of the ring and also transversely of the plane of the ring.

HENRY C. MIELKE.
